[21] Appl. No.: 7,533

[57] CLAIM

The ornamental design for a housing of a thermostat, as shown and described.

DESCRIPTION

[22] Filed: Apr. 26, 1993

FIG. 1 is a plan view of the front of the invention;
FIG. 2 is a side plan view as seen from left to right of
FIG. 1;

[52] U.S. Cl. D10/50; D10/49

FIG. 3 is a top plan of the invention, the bottom plan
view being a mirror image thereof;

[58] Field of Search D10/49, 50, 60, 101,

FIG. 4 is a perspective view of the invention; and,

D10/102, 126, 121; D13/162, 164; 236/46 R,
47, 94; 337/112, 320, 360, 380, 381, 414;
364/557; 374/142

FIG. 5 is a plan view of the invention, as seen from right
to left, of FIG. 1.
